UNITED STATES PATENT OFFICE.

ARTHUR DAVID JENKINS, ERNEST TELFORD BROOK, WILLIAM SHERRIFFS DAVIDSON,
AND PERCIVAL FREDERIC BRITTAINE, OF LONDON, ENGLAND.

TRIP VALVE FOR USE WITH THE AIR BRAKES OF RAILWAY VEHICLES.

Application filed August 29, 1924. Serial No. 734,979.

This invention refers to improvements in or relating to trip valves for use with the air brakes of railway vehicles.

The primary object of the present invention is to improve and simplify the construction and arrangement of the valve; to eliminate leakage of air, and reduce the friction of the working parts to a minimum, and to render the valve more positive and reliable 10 in operation.

According to the present invention we provide an automatic trip valve for use with the air brakes of railway vehicles, comprising 15 an upper valve chamber in communication with the brake pipe and a lower chamber having a controlled exit to the atmosphere, a valve stem arranged in said casing, a disc valve at the upper end of the stem co-operating with a seating in the upper valve chamber and adapted when the valve is tripped by the operating mechanism to admit air under pressure from the upper 20 chamber to the lower chamber, a second disc valve or baffle on the said valve stem adapted to co-operate by means of its periphery with a surrounding annulus or seating in such a manner that upon the initial operation of the first valve the air admitted to the lower 25 chamber will act upon the valve disc or baffle and complete the opening operation of the first valve and simultaneously put the said lower chamber into communication with the atmosphere, and a re-setting lever engaging 30 said valve spindle intermediate its length.

In order that the present invention may be clearly understood and more readily carried into effect, it is hereinafter described 40 with reference to the accompanying drawings, in which:—

Figure 1 is a sectional side elevation of a trip valve constructed in accordance with the present invention and showing the valve 45 and other parts in the position they assume when the valve is closed, but omitting the cam lever or other trip mechanism for operating the valve stem;

Figure 2 is a corresponding end elevation 50 of said valve, and

Figure 3 is a sectional plan view thereof.

Fig. 4 is a sectional view showing the improved trip valve as constructed for use in connection with vacuum brakes.

55 As shown and according to the present in-

vention the improved trip valve comprises a substantially cylindrical body portion or casting *a*, having an upper screw-threaded extension cap or plug *b*, a lower disc or closure plate *c* carrying a bushing *c*¹ for the valve spindle and detachably secured thereto by bolts or the like *d*, and an inlet connection *c*² to which the brake pipe *f* is screwed. The body portion of the cylinder *a* is divided by means of a transverse web *g* into an upper valve chamber *h* communicating with the brake pipe *f* and a two-part lower chamber *i*, *j* connected by means of a port *k*. The aforesaid two-part chamber *i*, *j* is so constituted by means of a second transverse web *l* which is centrally perforated and provided with a bush *m* through which slides the central operating spindle *n* of the valve *o*. The said valve spindle *n* carries at its upper end the aforesaid starting valve *o* which is provided with a leather or like washer *p* co-operating with a seating *q* formed by the web *g*. This valve *o* and its washer *p* are adapted to be secured in place on the reduced upper end of the valve spindle *n* between a lower metal washer *r* and a pair of lock nuts *s*. At or about the middle of its length the valve spindle *n* carries a further valve disc or baffle *t* which when the valve *o* is closed assumes the position shown in the drawings, practically closing the chamber *i*, *j*, but when the valve *o* is tripped air from the brake pipe *f* rushes in past the valve *o*, enters the chamber *i*, *j*, and, passing through the port *k*, raises the aforesaid disc or baffle *t* and escapes into the air by way of the exhaust port *u* and chamber or box *v*. The lower valve disc or baffle *t* is also secured on a reduced portion on the main spindle *n* by means of a suitable lock nut *w*, and by reason of the fact that no friction takes place between this valve disc or baffle *t* and its surrounding annulus or seating *x*, the said disc or baffle *t* may conveniently be constructed of metal or other rigid material and does not require to be accurately machined or fitted. Arranged in conjunction with the trip cock is a bell crank lever *y* which is fulcrumed at *z* to the body of the valve casting *a* in such a manner that its lower or short end projects through the port *u* into the exhaust chamber or box *v* where it is provided with a disc-shaped end 10 adapted to enter a transverse slot 11 formed in the body of the valve spindle *n*. The upper end 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

of the bell crank lever y is provided with a perforated eye 12, to which a suitable connection may be made whereby the valve o may be readily re-set, after it is operated. 5
5 The bell crank lever y is conveniently held in position on the horizontal fulcrum or pin z between a suitable packing washer 13 and a helical spring 14 interposed between the boss of the bell crank lever and the side brackets 10 15, 16 supporting the fulcrum pin z .

It will be seen from the construction described and shown in the drawings that the whole of the parts are readily accessible and that the valve spindle can be removed as 15 a whole by first removing the cap or plug b and the valve o and then withdrawing the said valve spindle from the lower end of the casing after the plate or disc has been removed.

20 It will also be seen that by the present invention no gland-tight joint for the valve spindle is required on the pressure side of the apparatus, thus considerably reducing the friction and minimizing the leakage 25 of air.

The valve stem itself may conveniently be moved by means of a cam lever hanging in such a position that it can be turned on its pivot by a tappet or arm set by the 30 signal. The cam lever may if desired be arranged to actuate the valve whichever be the direction in which the vehicle is travelling, or it may only actuate the vehicle when it is travelling in one direction, and not in 35 the other direction.

It will be obvious that the improved trip valve previously described may be used for vacuum brakes as well as with air brakes of the Westinghouse type. In the latter 40 arrangement the disc valve p' at the upper end of the stem n' and also the second disc valve or baffle t' on the stem would be suitably arranged; that is to say, the valve at the upper end of the stem would co-operate 45 with a seating q' arranged in the lower valve chamber, and the valve stem itself would move down instead of up. In this arrangement the upper chamber could be dispensed with and its place would be taken by a

socket piece adapted to be connected directly to the brake pipe f' . This construction is illustrated particularly in Fig. 4.

What we claim is:—

1. An automatic trip valve for use with the compressed air brakes of railway vehicles, comprising a casing divided by a transverse web into an upper valve chamber in communication with the brake pipe and a lower chamber having a controlled exit to the atmosphere, a valve stem arranged in said casing, a disc valve at the upper end of the stem co-operating with a seating in the upper valve chamber and adapted when the valve is tripped by the operating mechanism to admit air under pressure from the upper chamber to the lower chamber, a second disc valve or baffle on the said valve stem adapted to co-operate by means of its periphery fitting in a non-sealing relation within a surrounding annulus in such a manner that upon the initial operation of the first valve the air admitted to the lower chamber will act upon the valve disc or baffle and complete the opening operation of the first valve and simultaneously put the 75 said lower chamber into communication with the atmosphere, and a resetting lever engaging said valve spindle intermediate its length.

2. An automatic trip valve according to the claim 1, for use with the air brakes of railway vehicles in which only the one opening valve is arranged on the pressure or vacuum side of the apparatus, so that the spindle does not have to be packed 80 against air pressure, thus preventing leakage of air and reducing the friction on the working parts.

3. An automatic trip valve according to claim 1, in which the re-setting lever is also arranged on the atmosphere side of the valve.

In testimony whereof we have hereunto signed our names.

ARTHUR DAVID JENKINS.
